SUBMARINE SOUND SYSTEM

Jarold R. West, New York, N. Y., assignor to
Roger Williams, New York, N. Y.

Application June 29, 1936, Serial No. 87,867

2 Claims. (Cl. 177—386)

The present invention relates to the art of transmitting sounds through the body of a liquid. More particularly this invention embraces apparatus and methods for transferring vibratory sound energy from a producer thereof into a body of liquid.

This invention discloses a method of coupling a sound producing unit such as an electro-acoustical unit to a body of water, so that sound waves of comparatively great intensity will be set up within this body of water.

One object of this invention is to produce an electro-acoustical transmitting device, adapted to set up submarine oscillations, which shall be comparatively simple and cheap to construct, and which utilizes materials and parts readily available.

Another object of this invention is to afford means for readily transferring a large amount of sound energy to a body of water.

Another object of this invention is to afford ready means of transmitting intelligence by means of acoustical signals from one point in or on a body of water to another point in or on the same body of water.

A still further object of this invention is to afford a simple and cheap means of coupling the output of the ordinary telephonic loud speaker unit to a body of water.

Yet another purpose of this invention is to afford means which may readily be attached to vessels in motion or at rest, without the necessity of making special apertures in the hulls thereof, and which may be supplied with signalling energy from the radio telegraph, or radio telephone equipment usually present on such vessels.

Another purpose of this invention is to afford means for readily emitting signals from a submerged vessel of the submarine type either for normal communication purposes, or in case of emergency.

Yet another object of this invention is to supply music and speech, such as received from radio or wire broadcasting or from a phonograph pick-up, to a body of water so that bathers or swimmers therein may readily listen to such music or speech.

A still further object of this invention is to afford means for communicating with persons submerged in a body of water, such as persons learning to swim, or swimming beneath the surface of such water.

This invention is directed to an efficient cheap and simple coupling unit which will transfer sound from a reproducing unit to a body of

water. Broadly speaking, this invention consists of an elongated tube of suitable material which is immersed in a body of water and which has the portion thereof lying beneath the surface of water sufficiently impervious thereto so that immaterial amounts of water or none at all will enter the interior of this hollow tube. At one end of the tube is affixed a sound reproducing unit, such as a loud speaker unit, which, when actuated, sets up oscillations in the air present in the interior of the tube. The sound oscillations thus set up are transferred through the walls of the tube to the water surrounding it.

I have found that, in distinction from the practice previously used in the art of submarine signalling, sound energy may be very efficiently transferred from a column of air to a body of water, by means of lateral transmission through the walls of a tube of elastic material which forms a boundary between the column of air and the water.

The hitherto employed devices, transferred oscillating energy into a body of water by causing a flexible diaphragm of some nature to be actuated by the sound producing unit. Many devices have directly coupled a loud speaker diaphragm or oscillating armature to a diaphragm which formed the boundary between the water and air. My invention differs widely from these devices in that it sets up oscillations in a column of air and transfers these vibrations in a lateral fashion from this column of air into the surrounding liquid. In the devices of the prior art, elastic materials such as soft rubber were employed to insulate portions through which it was desired to have the sound travel, and the transmission of sound into the water was accomplished by the actual vibration of diaphragms constructed of materials such as sheet metal and the like.

It has been found that the devices employing moving diaphragms have encountered great difficulty in efficiently transmitting oscillations to such diaphragms. Such diaphragms are held at their peripheries and accordingly their freedom of motion varies widely at different points thereof. Various artifices have been proposed to ameliorate this difficulty, such as supplying energy to the diaphragm at a plurality of points, for example, to an annular portion of the diaphragm.

It has likewise been proposed to interpose an air chamber between the oscillating unit and the coupling diaphragm. This invention distinguishes from all these devices by using an air

chamber whose walls are constructed of a very elastic material such as soft rubber and which will transfer the oscillations directly therethrough without the employment of an intermediary coupling unit such as a diaphragm.

To more clearly explain my invention, I refer to the drawing hereunto attached where:

Fig. 1 is an elevation in cross section, and partly schematically, showing one form of my invention.

Fig. 2 is an elevation of the upper portion of another form of my invention, using a plurality of sounds producing units.

Fig. 3 is an elevation, illustrating schematically a radio receiver and a microphone coupled to a unit constructed according to this invention, and furthermore illustrating the transmission and reception of signals therefrom.

Fig. 4 shows in greater detail another embodiment of my invention, designed to be completely submerged in a liquid.

In Fig. 1, a loud speaking unit is shown at 10, including an outside containing shell 11, upon the end 12, of which is mounted a permanent magnet 13, wound with a coil 14, whose terminals 15, 16 are connected to a source of electrical oscillations, corresponding to the acoustical oscillations to be transferred to the water. A flexible diaphragm 18, of suitably magnetic material is held against a supporting member 17, at its periphery, by the attraction of magnet 13. The lower end of unit 10 is passed through an aperture in closure member 18, which member may be of wood, metal, or other suitable material. Unit 10 opens at its lower extremity into chamber 19, which is formed by the closure of a hollow tube 20, at both ends. The closure at the upper end is accomplished by member 18 and the closure at the lower end may be accomplished by another similar member 21. The tube 20 is preferably formed of soft rubber or other material of similar acoustical characteristics, and closure members 18 and 21 may be held within the ends of tube 20 by being forced therein against the natural elasticity of the walls of this tube. Tube 20 is submerged in a body of water 22.

While I have here shown a certain type of sound reproducing unit, it is to be understood that any suitable form of such unit may be used. For example, instead of the electro-magnetic type, the electro-dynamic type may conveniently be employed.

While not confining myself to any particular dimensions, I have found that for small types of water such as swimming pools and the like, and for sound reproducing units supplied with only a few watts of energy, a piece of soft rubber hose about 10 feet in length and about 2½ inches in external diameter is very satisfactory. This tube may have its walls ¼ inch thick.

In Fig. 2, sound reproducing units 30 and 31 are coupled together acoustically by means of the so called goose neck adaptor 33. The sound energy from each unit is thus combined together into a single sound conducting passage which forms the lower portion of this adaptor. This lower portion enters through closure member 18 into tube 20 in exactly the same fashion as shown in Fig. 1. The electrical coupling of units 30 and 31 by means of conductors 34, may be of the series fashion here indicated, and energy may be supplied thereto through lead wires 35, or else these units may be coupled in parallel as is well known in the electrical art. The determination of the particular method of electrical coupling in

any given case is dependent upon well known factors, including the relative impedance of the power source and the units. Tube 20 is closed at the lower end 28 by vulcanization.

In Fig. 3, the antennae 40, feeds picked up broadcast signals to a radio receiver 41 which may be supplied with a suitable ground connection, 42. The output of receiver 41, if not already at a sufficiently high power level, may be further raised in energy content by means of a suitable amplifier 43, whose output is fed into loud speaker unit 44.

It is to be understood that amplifier 43 may be unnecessary in many cases, or may be incorporated into the radio receiver itself. I have also shown a microphone 45, coupled by suitable conductors 46, to the input of amplifier 43. By suitable switching means (not shown) the amplifier 43 may be coupled either to the microphone or to the receiver. It is to be understood that if amplifier 43 is not used, the microphone 45, may be coupled into the circuit of the receiver 41, so as to raise the level of energy supplied by the microphone to a degree suitable for feeding sound producing unit 44.

The sound producing unit is coupled to the soft rubber tube 20, by means similar to those shown in Fig. 1, and the walls of tube 20 then transfer the sound energy into the surrounding water 22. While this transfer takes place over the entire submerged length of the tube 20, I have indicated diagrammatically the sound waves proceeding from a single point 46 of the tube 20, by means of concentric arcs 47, and at 48, I have shown the ear of a listener upon which ear these sound waves may impinge.

In Fig. 4, I show a comparatively rigid and impervious casing 50, which is closed at the top by means of a removable cover 51, affixed thereto by bolts 52, located around its periphery. The point of junction between cover 51 and casing 50 may either be ground to a close fit, or a suitable gasket may be interposed between these two members. Cover 51, may be provided with a suitable ring bolt 53, for the purpose of lowering and raising the entire unit with respect to the body of water in which it is submerged. The bottom of casing 50, is supplied with a projecting nipple 54, over which soft rubber tube 20 may be firmly clamped by means such as an ordinary hose clamp 55.

The bottom of tube 20 may also have its closure member 21 held firmly therein by another clamp 56, or may have its ends vulcanized together as shown in Fig. 2.

Within casing 50 is placed loud speaker unit 57, which may be threaded into the upper end of a passageway 58, extending through nipple 54, and affording an air passage for the sound to pass from unit 57, into air chamber 19.

Unit 57 is shown as being of the dynamic type and two conductors 60, 60 supply energy to the voice coil thereof by means of binding posts 61, 61. The field energy for this speaker may be supplied by conductors 62, 62 through binding posts 63, 63. The four conductors thus leading from unit 57 may be brought out of casing 58 by means of a pipe 64, which extends through cover 51, and is made of a length sufficient to reach above the surface of the liquid in which the entire structure is submerged.

Pipe 64, is conveniently lined with rubber insulation 65. I have found it however, of great importance that pipe 64 be made of sufficient cross section so that the conducting wires passing

therethrough do not completely fill the interior of this pipe, so that an air passageway is left therein.

Under such conditions, the functioning of the reproducing unit 51 seems to be more efficient, probably due to the reduction of the back pressure effect noticeable when such units are completely enclosed. The assembled structure shown in this figure is waterproof and may be submerged to any desired depth, provided only that pipe 64 reach to the surface.

The manner in which the various embodiments of my invention function has already been described and the details thereof will be apparent to those skilled in the art.

Where several units are employed as in Fig. 2, it is highly desirable that they be so connected that their respective sound outputs shall be in phase with one another, as otherwise a great loss of efficiency and a great amount of distortion may be experienced.

While I have described the reception of sound from my transmitting apparatus, as being accomplished directly by the human ear, yet it is to be understood that, especially for purposes of commercial signalling, the distance of transmission and/or ease of reception may be augmented by the employment of ancillary devices at the receiving end. One example of such an arrangement is the use of the microphone which may be either submerged in the water, or placed at the upper end of an air filled tube similar to that employed at the transmitter.

It is to be understood that while I have shown a radio receiver or a microphone feeding the reproducing unit of my system, any other suitable means for feeding this unit may be used, such as energy derived from wire broadcasting services or phonographic pick-ups.

It is to be noted that my invention distinguishes from prior devices by using the molecular vibration of the entire tube walls as a sound transfer or coupling means, rather than by the mass vibration of any diaphragm-like member as a whole.

5

I claim:

1. A device for transferring speech and music from air into water, including an elongated tube of elastic material substantially submerged in water and filled with air, the walls of said tube constituting a homogeneous medium for the propagation of sound energy laterally therethrough substantially wholly by molecular vibration of said walls, rather than by mass vibration thereof, and an electro-acoustical transducer located at one end of said tube, said transducer including a vibrating diaphragm substantially completely closing one end of said tube and means extending from one side of said diaphragm into the free air above said water, whereby the air in said tube is subjected to the pressure waves from one side of said vibrating diaphragm, and whereby substantially no back-pressure effects upon the other side of said diaphragm hinder the motion thereof so as to cause acoustical distortion.

25

2. A device for transferring voice frequencies from air into water, including an elongated tube of elastic material, means for closing both ends of the tube, one of said closure means comprising one side of an imperforate acoustical diaphragm, means for vibrating said diaphragm at voice frequencies and means for keeping substantially normal atmospheric pressure upon the other side of said diaphragm, whereby differing pressures of air can exist upon opposite sides of said diaphragm.
